CODING ARRANGEMENT

Hans Hess, Wilhelmshaven, Germany, assignor to Olympia Werke A.G., Wilhelmshaven, Germany

Filed June 19, 1961. Ser. No. 160,964

Filed June 19, 1961, Ser. No. 166,964
Claims priority, application Germany June 23, 1960
24 Claims. (Cl. 197—1.5)

The present invention concerns a coding arrangement, particularly suitable for being incorporated in a business machine, and a business machine comprising a coding arrangement and particularly a business machine of the type of typewriters, adding machines and similar machines, particularly electrically operated typewriters, for the purpose of converting the items of information which are typed or printed, as for instance characters, figures and symbols, as well as special control commands introduced by the operation of special keys, into coded electrical signals composed of a predetermined code element combination representing the items of information which are being typed or the special control commands introduced into the machine.

There exist well-known code converting or translating arrangements for converting information introduced in accordance with one code system into output signals according to a different code system. Also there are known devices for converting items of information which are printed by means of a keyboard machine into electrical code element signal combinations.

However, it has been found that all these known devices are not entirely satisfactory. One of the reasons for this disadvantage of known devices is that the known arrangements are rather involved and call for an excessive number of electrical components which greatly increase the cost of the apparatus and also require an undesirably great amount of space. On the other hand, it is highly desirable to provide for a coding arrangement which can easily and at comparatively low cost be incorporated into a standard business machine and may even be added as an accessory to an existing business machine. A further disadvantage of known devices consists in the fact that the manual operation of the keys of a keyboard producing printed records of items of information cannot be carried out without substantial differences between the time period applying to the actuation of different keys by the operator whereby in many cases the proper generation of coded output signals is greatly impaired.

It is therefore a main object of the present invention to provide for a coding arrangement, particularly suitable for being incorporated in a business machine, and for a business machine incorporating a coding arrangement of the above described type, which avoids all the above mentioned disadvantages.

It is a further object of this invention to provide for such an arrangement which requires a comparatively small number of more or less standard components, requiring comparatively small space and therefore permitting their incorporation into a standard business machine of the above mentioned types or even to be mounted as an accessory in an existing standard business machine.

With above objects in view a coding arrangement, particularly suitable for being incorporated in a business machine, comprises, according to the invention, in combination, a plurality of information input means respectively associated with different items of information and each including normally closed circuit interrupting means opening the respective circuit for an indefinite period of time upon actuation of the respective information input means; a plurality of code element output means changeable between an inoperative and an operative condition, selected combinations of operative ones and inoperative

2

ones of said code element output means, respectively, representing different code signals respectively associated with different ones of said items of information; a source of energy; and circuit means operatively interconnecting

5 said source of energy, said current interrupting means of said information input means, and said code element output means for operating the latter upon actuation of any one of said information input means, said circuit means including selector means responding to actuation of any

10 one of said information input means and to the resulting actuation of the respective circuit interrupting means irrespective of the duration of the resulting circuit interruption, and for rendering, upon actuation of a particular one of said information input means, at least one selected

15 one of said code element output means ready for being changed from inoperative condition to operative condition so as to predetermine thereby a particular combination of operative and inoperative code element output means which represents the same item of information as

20 said particular actuated information input means, and control means actuatable by any one of said information input means for connecting, upon actuation of said particular information input means, said source of energy with those selected code element output means which

25 are rendered ready for being changed from inoperative to operative condition within said particular combination thereof, and for thereby effecting the change of said selected code element output means from inoperative to operative condition, whereby a code signal is delivered

30 by said selected code element output means which represents the same item of information as the particular information input means that is being actuated.

In another aspect of this invention, a business machine adapted to be used for printing different items of information such as characters, figures and symbols, includes a coding arrangement, comprising, according to the invention, in combination, a plurality of control means comprising information input means including each a type printing member movable between an idle position and a printing position, each of said information input means being respectively associated with different items of information and each including at least one and a maximum of two normally closed circuit interrupting means operable by the respective printing member and opening the respective circuit for an indefinite period of time upon actuation of the respective information input means resulting in moving the respective printing member to its printing position; a plurality of code element output means changeable between an inoperative and an operative condition, selected combinations of operative ones and inoperative ones of said code element output means, respectively, representing different code signals respectively associated with different ones of said items of information; a source of energy; and circuit means operatively interconnecting said source of energy, said current interrupting means of said information input means, and said code element output means for operating the latter upon actuation of any of said information input means, said circuit means including selector means responding to actuation of any one of said information input means and to the resulting actuation of the respective circuit interrupting means irrespective of the duration of the resulting circuit interruption, and for rendering, upon actuation of a particular one of said information input means, at least one selected one of said code element output means ready for being changed from inoperative to operative condition so as to predetermine thereby a particular combination of operative and inoperative code element output means which represents the same item of information as said particular actuated information input means, and control means actuatable by any one of said information input means for connecting, upon actuation

of said particular information input means, said source of energy with those selected code element output means which are rendered ready for being changed from inoperative to operative condition within said particular combination thereof, and for thereby effecting the change of said selected code element output means from inoperative to operative condition, whereby a code signal is delivered by said selected code element output means which represents the same item of information as the particular information input means that is being actuated for printing such item.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 illustrates diagrammatically the keyboard of a typewriter equipped with means for carrying out the invention;

FIG. 2 and FIG. 3 together represent a schematic circuit diagram of an arrangement according to the invention, FIG. 2 constituting the right half of the diagram and FIG. 3 constituting the left half of the diagram, the connection between the two diagrams being represented by corresponding identical numerals 13-18 at the respective ends of the particular line portions of the circuit;

FIG. 4 is a diagrammatic lateral view of a type lever arrangement and drive means of an electrical typewriter together with some contacts operated by the type lever arrangement and corresponding to certain contacts shown in FIGS. 2 and 3; and

FIG. 5 is a diagrammatic lateral view of a shift key and self-locking shift key arrangement of a typewriter including certain contact means corresponding to those shown in FIGS. 2 and 3.

Before entering into a description of the arrangement illustrated by the drawings, I wish to state that the arrangement according to the present invention comprises the characteristic feature of having a plurality of code element output means of any desired type and a plurality of selector means connected in parallel for selecting the circuit elements required for rendering the individual code element output means, according to the particular code system, operative and for substantially simultaneously connecting these output means with a source of electric energy. The selector means are under the control of contacts operated by the individual keys of the keyboard of the machine but the reaction time of these selector means is independent of the variable duration of the manual operation of the keys because the selector means are preferably relays which are normally energized through the key-controlled contacts which are connected in series, which act as circuit interrupting means and are arranged in groups and sub-groups for causing a reaction of those relays which by their combination represent in accordance with the desired code system that type of information with which the particular actuated key is associated. A highly advantageous feature of the arrangement according to the invention is that in any case at least one of said contacts but never more than two contacts have to be operated simultaneously.

Another advantageous feature of the invention is that all the above mentioned contacts which are operated by the standard keys of the keyboard machine are mounted within the business machine on a preferably common support which feature greatly facilitates the construction of the arrangement and its incorporation into a business machine.

According to the invention the relays constituting the selector means are constructed to have an extremely short cut-off time and a preferably adjustable comparatively slow return time whereby the operation of the coding

device is entirely independent from the duration of the depression of the individual keys.

The code element output means are preferably components of a perforating device for producing perforated coded tapes so that simultaneously with the typing or printing of an alpha-numeric text a punched or perforated tape is produced which stores in coded form the simultaneously typed or printed text.

It is further to be noted that the arrangement according to the invention is so constructed that the standard keyboard of a typewriter can be used without any change. Consequently, and due to the separation of typewriter, coding arrangement and perforator the entire arrangement is advantageously different from all known arrangements provided for similar purposes.

On the other hand, the arrangement according to the invention makes it also possible to operate for instance a tape perforator forming part of a Teletype arrangement by means of a plurality of separate typewriters equipped with the coding arrangement according to the invention.

Since in standard tape perforating and teletyping arrangements it is necessary to switch from the transmission of characters to the transmission of figures and symbols, and vice versa, it is to be noted that with the arrangement according to the invention the standard shift key arrangement of a typewriter can be used for the just mentioned switching between different types of transmissions. In addition, a business machine according to the invention is equipped with blocking means for blocking the operation of all those keys which would produce items of information which are not desired to be used within the actually used code system.

The following description of a certain embodiment of the invention refers by way of example to a coding arrangement incorporated in a fully electrical typewriter capable of printing characters, figures and symbols at a speed of 18 to 20 items per second. Moreover the illustrated arrangement serves to operate a tape perforator but, as mentioned above, the code element output means may also be used analogously for issuing any other type of coded signals. The specific electrical components illustrated and described may be exchanged against equivalent other control or circuit components without departing from the essence of the invention.

Referring now to the drawings, FIG. 1 illustrates a keyboard 1 of a fully electrical typewriter equipped with the specific arrangement according to the invention. As can be seen, all the character keys 2, and also the figure and symbol keys 3 are arranged as per the usual arrangement in a typewriter keyboard.

The entire coding arrangement according to the invention is rendered operative by means of a control member 4 arranged at the right-hand end of the keyboard 1 and marked with the position indications "Off" and "On" and operating a main switch 5 which is shown in FIG. 3. Operatively connected with the switch 5 and the control member 4 is a mechanical blocking means 6 shown diagrammatically in FIG. 4 whereby the character keys 2 can be blocked when the figure and symbol keys 3 are to be used, and vice versa.

The key 7 is the conventional back space key while for the shifting from line to line the shift key 8 marked LF is provided. The two keys 9 marked CR serve for causing the carriage return. The shift key 10, marked accordingly, serves for shifting from lower case characters to upper case characters. At the left-hand end of the keyboard keys 11 and 12 are provided by means of which, as will be described further below with reference to FIG. 5, during a coding operation the shift from transmitting characters to transmitting figures or symbols, or vice versa, is to be effected. It is to be understood that the keys assigned to umlauts ä, ö and ü as well as all those keys which are associated with controls or symbols which are not to be translated into coded signals, e.g.

according to the international telegraphic code, are blocked during coded signal transmission by blocking means not shown in detail in the drawings.

Referring now to FIGS. 2 and 3, a source of energy is provided by a transformer 62 connectable by lines 60 and 61, upon closing of the main switch 5, to an outside source furnishing A.C. line voltage. The secondary of the transformer 62 is connected with a full-wave rectifier 39 so that at its negative and positive terminals direct current voltage is available. The positive terminal is connected by a line 131 to a junction point 40, while the negative terminal is connected to a line 130 which continues as a line 38 containing a resistor 37. From the junction point 40 positive voltage is taken across a resistor 41 and through line 20 (including the connecting terminals 13) to the various consumers of energy. On the other hand the negative potential is taken from line 38 through line 46 to junction point 45 and across the connecting terminals 14 into line 19 described further below.

In the left upper portion of FIG. 3 a plurality of relay coils R_1 to R_5 , R_{34} and R_{35} is shown which are connected at one end with line 38. The other ends of the just mentioned relay coils are connected through lines 24, 25, 30, 33, 34, 35 and 36, respectively, and through various junction points 23, 26, 27, 29, respectively to a common junction point 21 carrying the positive potential supplied by line 20. Each of the above mentioned lines emanating from the positive ends of the various relay coils contains a series of normally closed contacts marked, for instance in line 24, B_1 , ?, D_1 , E etc., the marking of these various contacts indicating with which ones of the various keys 2, 3, etc. of the keyboard 1, respectively associated with the corresponding characters, figures or symbols, the particular contacts are operatively connected as described further below. It is to be noted that the above mentioned coils R_1 - R_5 , R_{34} and R_{35} constitute the energizing means of relays constituting the selector means according to the invention. The distribution of the various coils in relation to the above mentioned lines and to the various normally closed contacts therein corresponds to a standard international code system. The entire arrangement of the normally closed contacts and the distribution of the corresponding lines in relation to the various relay coils is so chosen that for no item of information to be transmitted to the code element output means described further below, more than two of the above mentioned normally closed contacts are to be operated. For instance, for the letter B only one contact B_1 in line 24 and one contact B_2 in lines 33, 31 is provided. For the letter E only one contact E in line 24 is provided.

As long as all the series connected above mentioned contacts are in closed position all the relay coils R_1 - R_5 , R_{34} and R_{35} are energized. Opening contact E would result in deenergization only of the coil R_1 . Simultaneous opening of contacts B_1 and B_2 , however, would result in deenergization of the coil R_1 and of the coils R_4 and R_5 because the line 31 is branched at junction point 32 into two lines 33 and 34 leading to the coils R_4 and R_5 . Both these examples are in accordance with the international code system used for instance for teletypewriter code perforated tapes, according to which the character E is represented by only one hole in the first row of holes while the letter B is illustrated by one hole in the first row, one hole in the fourth row and one hole in the fifth. From FIGS. 2 and 3 it can easily be seen that the opening of contact B_2 affects both the lines 33 and 34 and therefore both the relay coils R_4 and R_5 .

It is not believed to be necessary to go into details regarding the function of the various individual contacts. As far as specific cases are concerned these will be discussed and described further below. Anyway, it can be seen and understood readily that any one of the contacts arranged between the junction points 21 and 23 will, when opened, deenergize two relays namely the

coils R_1 and R_2 . Similarly any contact between the junction points 29 and 32 will, when opened, deenergize simultaneously the coils R_4 and R_5 . Any one of the contacts between the junction points 26 and 29 will, when opened, deenergize three relays namely the coils R_3 , R_4 and R_5 . Finally two contacts Bu and RT are arranged in the positive potential line 20 ahead of the junction point 21. Therefore opening of either one of these two contacts will deenergize all of the relay coils R_1 - R_5 , R_{34} and R_{35} . The function of the special contacts Bu and RT will be described further below. At this point it may suffice to state that the contact Bu is only opened when by actuation of one of the keys 11 or 12 an advance signal is to be transmitted announcing that thereafter either characters or figures and symbols will be transmitted. On the other hand, the contact RT is operated under the control of the return key switch RT' shown in FIG. 3 and described further below.

In order to assist the reader in properly interpreting the circuit diagrams FIG. 2 and FIG. 3 it is to be understood that every one of the relays comprising the coils R_1 to R_5 , R_{34} and R_{35} also comprise a plurality of relay contacts operated upon energization or deenergization of the respective coils. For the sake of clarity of the diagrams the relay contacts operated by the respective coils are not shown in position adjacent to the respective coil but rather at that place in the circuit where they carry out their function. For the purpose of identification and correlation the various relay contacts operated by one particular relay coil are designated by r_1 , r_2 , r_3 (wherever it is applied) with the addition of the designation of that coil which operates the particular contact. For instance, the coil R_1 operates the contacts r_1R_1 , r_2R_1 , the coil R_{35} operates the contacts r_1R_{35} , r_2R_{35} and r_3R_{35} . The same system applies to other relays that will be described hereafter for instance the relay having the coil 48 and designated "Imp." and the relay having the coils R_1 to R_{1V} and R_A - R_C . It is further to be understood that in FIGS. 2 and 3 all components are shown in normal position which they assume as soon as the main switch 5 is closed. This means that all the series-connected contacts in the lines 22, 24, 25, 30, 31, 33, 34, 35 and 36 are shown in closed position; the coils R_1 to R_5 and R_{34} and R_{35} are assumed to be energized so that the contacts operated thereby are shown in the deflected position resulting from energization of the respective coils; however the relay coils 68 and 48 are to be assumed as not being energized so that the contacts operated thereby are shown in their respective position of rest; the switch contact A in FIG. 2 and the control contact Zi in FIG. 3 are shown in their normal, not actuated position, and the relay coils R_1 - R_{1V} and R_A - R_C are assumed not to be energized so that the contacts respectively operated thereby are shown in their respective position of rest.

As can be seen from FIG. 3, the relay coils R_1 - R_5 , R_{34} and R_{35} each operate one first relay contact r_1R_1 , r_1R_2 , r_1R_3 , r_1R_4 , r_1R_5 , r_1R_{34} and r_1R_{35} connected in series with each other in the line 42 between junction points 40 and 44. The function of these first contacts will be described further below. The second and third contacts operated by the above mentioned relay coils form part of the selector means and control the energy output lines 50, 51, 52, 53 and 54, respectively which serve to complete a circuit between the negative terminal of rectifier 39 and the respective inputs of the code element output means 55-59. In the present example the code element output means are shown as electromagnets suitable for actuating hole punches of a perforator device HP described further below. Again it is stressed herewith that these code element output means could as well be simply output terminals for issuing signal combinations in five channels corresponding to a five-element code. However, even if any one or a plurality of the above mentioned second and third switch contacts operated by the coils R_1 to R_5 , R_{34} and R_{35} are moved to closed position, the corresponding

code element output means 55-59 would not be rendered operative unless the relay contact r_2 Imp is moved to closed position by energization of the corresponding relay coil 48 "Imp."

Although the operation of the so far described arrangement will be described in further detail below it is to be mentioned already at this point that the selector relays i.e. the coils R₁ to R₅, R₃₄ and R₃₅ are operated with closed circuit current supply so as to hold the relay contacts operated thereby continuously in the deflected positions as shown in FIG. 3, and to permit these contacts to return, under the action of return means not shown but conventionally known, to their position of rest as soon as the respective relay coil is deenergized. The above described selector relays are so constructed that they have an extremely brief cut-off time while having a comparatively delayed response or return when they are again energized. This has the effect that the above mentioned relays react immediately when any one of the respective series-connected normally closed control contacts in lines 24, 25, 22, 30, 31, 33, 34, 35 or 36, or any one of the contacts Bu or RT is opened, even if this opening of any one of these contacts takes place during only a very brief period of time i.e. a very short-time actuation of the respective keys of the keyboard. On the other hand, when the respective key is released again so that the respective contact is closed again, the relay contacts controlled by the respective coils remain in their respective position of rest for a certain period of time depending upon the amount of delay in the return of the respective relay contacts after re-energization of the respective coil. Hereby a sufficiently long energization of the code element output means is assured when any one or more of them is or are placed in operative condition.

Now the control means for controlling the supply of energy to the code element output means will be described with reference to FIG. 3. As long as all of the coils R₁ to R₅, R₃₄ and R₃₅ are energized, their respective first contacts r_1 R₁, r_1 R₂ etc. described above and connected in series between the junction points 40 and 44 are held in the position shown in FIG. 3. In this position the free ends of these series-connected contacts are in engagement with the respective stationary contacts 118 to 124. Inserted in the connection between the junction points 40 and 44 is a capacitor 43 which, as can be seen from the diagram, is kept in charged condition as long as the series-connected relay contacts between junction points 40 and 44 are in the closed condition shown. A relay coil 48 is connected in a line 47 emanating from the junction point 44 and containing second stationary switch contacts 111-117 which are so arranged that whenever any one of the above mentioned series-connected relay contacts in the line between junction points 40 and 44 returns, under the action of means not shown, to its respective position of rest upon deenergization of the respective relay coil, a circuit is closed between one terminal of the capacitor 43 through line 47 to the relay coil 48 so that the capacitor 43 is able to discharge across this coil 48. Hereby the coil 48 is energized and moves certain relay contacts operated thereby from their position of rest into a circuit-closing position. The first one of these relay contacts namely r_1 Imp is connected together with a variable resistor 49 in parallel with the capacitor 43 so that its discharge time is automatically regulated by this parallel circuit whenever the discharge of the capacitor 43 is started. The second relay contact operated by the coil 48 is the above mentioned contact r_2 Imp so that, substantially simultaneously with the closing of an output circuit for one or more of the code element output means 55-59 also the energy supply from the energy source 39, 62 is established via the junction point 40.

As can be seen from FIG. 3, some of the second and third relay contacts operated by the coils R₃₄ and R₃₅ are interconnected in such a manner that upon energization

of the just mentioned relay coils specific combinations of the code element output means 57, 58 and 59 are simultaneously effected. This is in accordance with the above mentioned international code system.

Under the assumption that in the present embodiment, by way of example, the code element output means 55-59 are electromagnets operating hole punches of a conventional perforator HP means are further provided for moving the tape across or through the perforator arrangement HP. These means may consist of a motor 65 supplied from the outside source of energy via junction points 63 and 64 as soon as the main switch 5 is moved to closed position. The motor 65 drives the tape feed of the perforator HP by means of an electromagnetic clutch 66 as diagrammatically indicated. The electromagnet means of this clutch 66 may be energized for the purpose of transmitting power from the motor 65 to the perforator, in two ways. Since every introduction of an item of information into the coding arrangement according to the invention, or, in other words, every output of a code element combination requires a new position for the respective tape, every energization of the relay 48 is utilized, by the closing of the third relay contact r_3 Imp to connect the electromagnetic clutch 66 between line 130 and junction point 40. The clutch 66 is to be assumed as being of the conventional type which carries out upon every energization thereof only one turn sufficient and calculated to feed the tape in the perforator HP the desired distance required for making room for the next following perforation. However, there are certain cases when a different type of continuous tape feed is desired. In this case the manually operable switch 67 may be moved into closed position so that a continuous energy supply from junction point 40 into the clutch 66 can be effected. Finally, there are cases where a return or back movement of the tape is desired while at the same time a previously produced set of punched holes is to be obliterated. This can be effected by manual operation of the switch 69 marked RT' whereby an electromagnet 68 is energized which, by conventional means not shown, causes a one-step return movement of the tape while at the same time, through opening of the contact RT in FIG. 2 it causes all the hole punches energized by the electromagnets 55-59 to punch an obliterating series of holes into the tape.

Referring now to FIG. 4, on the typewriter frame 71, shown partly in section in a diagrammatic way, a support strip 70 is mounted in some suitable manner which carries the sets of control contacts described above and arranged to control the relay coils R₁-R₅, R₃₄ and R₃₅, respectively. The arrangement is such that the contacts to be operated are so located that they can be actuated by some portion of the respective type levers of the typewriter. By way of example FIG. 4 illustrates those normally closed contacts which appear in FIGS. 2 and 3 as B₁ and B₂. In FIG. 4 and the following description these particular contacts are designated by the reference numerals 73 and 74. The elastic supports 75 and 76 of these contacts, respectively, carry at their free ends nipples 77 and 78, respectively, which are in series-engagement with a further nipple 79 carried by a separate elastic support as shown in FIG. 4. The elastic support 75 co-operating with the contact 73 and the elastic support carrying the contact 73 constitute part of the line 24, and similarly the elastic support 76 and the elastic support carrying the contact 74 constitute part of the line 31 as intimated in dotted lines in FIG. 4.

It will be understood that the normally closed contacts 73 and 74 will be moved out of contact with the corresponding blades 75 and 76, respectively, when the type lever 80, constituting a conventional part of an electrically operated typewriter, is moved for the purpose of printing in the direction of the arrow 93 so that the extension 80a hits the nipple 79. In a generally known manner the key 2 is connected by the stem 81 with a multi-arm lever

82 which is carried by links 83 and 84, swingable about respective pivots 85 and 86, so that upon actuation of key 2 the lever 82 moves in downward direction remaining parallel with itself. When this movement takes place the extension 82a actuates via conventional intermediate members a lever 89 pivoted at 91 so that the drive member 87 is caused to engage a continuous rotating drive roller 88 whereby the lever 89 obtains a rotary impulse about its pivot 92 (in lever 80) and thereby causes the lever 80 to swing about its pivot 90 in the direction of the arrow 93. Consequently the extension 80a, connected by a spring 94 with a point 91, is moved into engagement with the nipple 79 thereby opening the contact connection of the contacts 73, 74 with the respective blades 75, 76.

It can be seen from FIG. 4 that the arrangement of the contacts 73, 74 as normally closed contacts entails a further advantage because, if the contacts 73, 74 were constructed as normally open contacts, the closing of these contacts under action of the type lever 80 would probably result in a bouncing thereof which certainly would result in an inaccurate operation of the control arrangement.

FIG. 5 illustrates that portion of the business machine or typewriter which contains the shift key 12 and the self-locking shift key 11. Normally the shift key 12 serves for shifting the typewriter operation from lower case letters to upper case letters while the self-locking shift key 11 serves to lock the shift key 12 in its depressed position. However, for the purposes of the present invention the self-locking shift key is so constructed in reference to the shift key 12 that the key 11 can be used additionally for effecting desired control operations of the electrical equipment described above.

The self-locking shift key 11 is operatively connected with the arrangement for shifting to typing upper case characters, otherwise not described or shown in detail, by means of a lever 95 which is supported for movement parallel with itself by means of links 96, 97 pivotable about pivots 98, 99, respectively. In well-known manner the stem 100 carrying the key 11 is mounted pivotable at the pivot 100' on the lever 95 and carries an extension 101 which, in depressed position is capable of locking itself in that position by the engagement of the hook 102 with the edge of the holding device 103.

When the key 11 is depressed the forward end of lever 95 acts by means of the portion 106 on the normally closed contact arrangement Bu so as to open this contact arrangement when the extension 101 and the hook 102 reaches its lowest position. As soon as the key 11 is released and the hook 102 is arrested by engagement with the edge of member 103 in a position slightly higher than its lowest position, the contact Bu is closed again.

On the other hand the stem of key 12 is not directly connected with lever 95 but has a lateral projection 150 which upon depression of key 12 forces the lever 95 downward so that again the member 106 will open the contact Bu. However the stem of key 12 has an extension 104 carrying a pin 107 guided by member 109 and elastically supported by spring 105, which pin 107 carries a blade 108 which, in the lowest position of key 12 enters between the contact members of the above mentioned contact Fg connected in the line 52 so as to interrupt the circuit for the code element output means 57. This is in accordance with the standardized code signal desired to be furnished when the key 12 is depressed.

The diagram of FIG. 2 further shows an automatic control arrangement arranged between the lines 19 and 20. Through the common connection terminals 13 and 14, respectively, the lines 19 and 20 are constantly supplied with negative and positive potential, respectively. A first and a second group of relays is connected between lines 19 and 20 in the following manner. The first group of relays comprises the relay coils R_I, R_{II}, R_{III} and R_{IV}. The second group comprises the relay coils R_A, R_B and R_C. All these relay coils are connected in a cascade arrangement in view of the specific interconnection and rela-

tive arrangement of contacts operated by the respective coils just mentioned above. Interposed in the respective connections between line 20 and the corresponding ends of the above mentioned relay coils of the first and second 5 group are switch contacts of which the contact A is manually operable, for instance by operation of the key 9 in FIG. 1, while the other contacts r₁R_A, r₁R_B, r₁R_C, r₁R_I, R₁R_{II} and R₁R_{III} are moved from their shown positions, respectively, into their second position by the 10 energization of the respective relay coil designated according to the above described system. As can be seen each of the just described switch contacts is connected at one end across a capacitor C_I, C_{II}, C_{III}, C_{IV}, C_A, C_B and C_C, respectively with the common supply line 19. It can be seen further, that in normal position the switch contact A connects the respective capacitor C_I continuously with the supply lines 19 and 20 so that the capacitor C_I is ordinarily charged. In contrast therewith, the other above 15 mentioned capacitors of this automatic control arrangement are normally disconnected from the line 20 by the normal position of the respective relay contacts so that these capacitors are normally not charged.

As will become apparent from the description below of the operation of the entire arrangement, the just described automatic control arrangement serves the only purpose to produce automatically a code signal composed of four consecutive code signals, or in the case of perforating a tape, a consecutive series of four perforations whenever the control command for carriage return is 20 given because such a series of perforations is required if the perforated tape is used for controlling a card puncher.

Operation

For all practical purposes, in an embodiment of the invention incorporating code element output means servicing a tape perforator, the various components of the arrangement are so arranged, that the energy supply 39, 62, the one-turn clutch 66 and the output electromagnets 55-59 are comprised in the perforator HP not otherwise illustrated in detail. It may be further assumed that this 25 perforator arrangement including the above mentioned components is connected with the typewriter, not shown in detail, by means of a cable and a multi-prong plug and socket connection.

All the control elements existing within the typewriter 30 are passive elements. All the relay coils R₁ to R₅, R₃₄ and R₃₅ are, as soon as the main switch 5 is closed, in energized condition across all the contacts mounted on the support strip 70 shown in FIG. 4. Whenever one of the keys 2 is actuated the respective normally closed set of contacts, for instance 73, 74, is actuated by the lever extension 80a so that these contacts 73, 74 are opened without bouncing as described above. Those relay coils which are connected in circuit with the particular opened 35 control contacts, namely one or more of the relay coils R₁ to R₅, R₃₄ and R₃₅, are deenergized and thereby the respective relay contacts for instance 73, 74, are immediately opened even if the respective key 2 is only lightly touched. The provided return delay of the just mentioned 40 relays causes the respective relay contacts r₁R₁, r₁R₂, r₁R₃, r₁R₄, r₁R₅, r₁R₃₄ and r₁R₃₅ to remain in their respective second position long enough to assure that the minimum energization period of the relay coil 48 is sufficient to cause the required flow of energy through the output 45 lines 50-54 and, in the present example, the energization of the electromagnets 55 to 59 and of the electromagnetic clutch 66 so as to enable the latter elements to carry out their assigned function.

Specifically, the operation of the arrangement will now 50 be described by way of example in reference to the actuation of the character key B. As mentioned above, in a five element code system this may require the punching of one hole each in the first, fourth and fifth row of the tape to be perforated.

In the manner above described, the extension 80a of

the lever 80 opens upon actuation of the key 2 the normally closed contacts 73 and 74 which appear in the diagrams of FIGS. 2 and 3 as contacts B₁ and B₂, respectively. The contact B₁ is located in the line 24 of the relay coil R₁, while the contact B₂ is located in the line 31 which leads both to the relay coils R₄ and R₅. Consequently, the opening of the contacts B₁ and B₂ deenergizes the relay coils R₁, R₄ and R₅. Hereby the respective change-over relay contacts r₁R₁, r₁R₄ and r₁R₅ in line 42 are moved to their respective second position whereby the previously charged capacitor 43 is connected via line 47 across the relay coil 48. Consequently this relay coil 48 is energized and moves the respective relay contacts r₁Imp, r₂Imp and r₃Imp into closed position.

Simultaneously with the just mentioned change-over relay contacts also the second selector relay contacts r₂R₁, r₂R₄ and r₂R₅ are permitted to drop off and to close in their respective position of rest the circuits for the output lines 50, 53 and 54 whereby in the present example the electromagnets 55, 58 and 59, respectively, for operating the corresponding perforating punches are made ready for energization.

The just mentioned electromagnets are now energized in view of the closing of the contacts r₂Imp which may have occurred immediately before the closing of the output circuits 55, 58 and 59, or immediately thereafter, the relative duration of the energization of the relay coils of the selector arrangement and of the relay 48 being adjusted properly in relation to each other. It can be seen that in this manner any desired combination of code elements or code signals will be automatically produced in a manner similar to that described with reference to a specific example.

It can be seen that the above described arrangement has the effect that ordinarily the electromagnets 55-59 or any selection thereof, for operating corresponding perforating punches will be energized simultaneously with the energization of the one-turn clutch 66. However, since the comparatively small magnetic fields of the electromagnets 55-59 are built up faster than the more sizable magnet field of the clutch 66, the electromagnets 55-59 controlling the perforating arrangement will respond, as is desirable and advantageous, more rapidly than the electromagnetic means of the clutch 66. Thus the desired perforation will be effected before the engagement of the clutch members of the clutch 66 causes a one-step feed movement of the tape which is being perforated. As a matter of fact a desired difference in the speed of operative response of the electromagnets 55-59, on one hand, and the electromagnetic clutch 66, on the other hand, can easily be predetermined by suitable selection of the respective data for these electromagnets.

The duration of the current flow for the electromagnets 55-59 and for the electromagnetic clutch 66 is determined generally by the parameters of the relay coil 48, and the duration of the energization of this coil 48 is, in turn, predetermined by the discharge time of the capacitor 43. The capacitor 43 discharges only after the relay coil 48 has been energized and has moved its respective contacts, and in particular the discharge of the capacitor 43 takes place across the relay controlled contact r₁Imp and the adjustable resistor 49 the resistance whereof is smaller than that of the coil 48. Of course, the discharge time of the capacitor 43 can be varied and adjusted by varying or selecting the magnitude of the resistance of the resistor 49.

The electromagnets 55-59 or any selected ones thereof cause the perforation of the tape in the perforator HP. This is done during the period of time required for one revolution of the one-turn clutch 66. Details of the perforator do not require any description since these are well-known in the art and do not form part of this invention. Within the same period of time the tape is moved forward one step in conventional manner.

Returning to the above described example of producing

5

a code element combination representing the character B in the form of a corresponding perforation of the tape, it will be understood that after the deenergization of the relay coil 48, after re-energization of the relay coils R₁, R₄ and R₅, and after re-charging the capacitor 43, the whole arrangement is again ready for dealing with the next item of information to be processed.

10

As mentioned above, the switching from the transmission of characters to the transmission of letters and symbols is carried out by using the conventional mechanism for switching the typewriter from lower case characters to upper case characters with the only difference that the self-locking shift key 11 which also actuates the lever 95 and the contact Bu, can be operated independently of the key 12 because the lateral projection 150 of the key arrangement 12 only abuts against lever 95. Consequently, the key 11 is used for switching in the present example to the transmission of upper case characters while at the same time a blocking arrangement, not shown in detail in the drawings, is operated for blocking the figure keys 3 and also causes the issue and transmission of a coded signal announcing the start of transmission of characters by means of an output of energy through the output lines 59 to 59 simultaneously whereby in the present example all of the hole punches of the perforator are operated simultaneously in accordance with the international code.

20

Whenever it is desired to issue the above mentioned announcement signal, the key 11 is actuated as explained above so that by depressing the lever 95 with its member 106 the contacts Bu (FIGS. 2 and 5) are separated and the circuit correspondingly interrupted. The circuit interruption at the contacts Bu occurs at the moment when the hook portion 102 of the extension 101 is in its lowest position. However as soon as this hook 102 slips around the lower edge of the member 103 into its locking position the member 106 moves just enough in upward direction to permit the contact Bu to close again. In this position of the self-locking key 11 all the figure and symbol keys 3 are mechanically blocked against operation by conventional blocking means not shown in the drawing so that now only those items of information, in particular upper case characters, can be typed (and correspondingly converted into code element combinations) which are ordinarily typed or printed by actuation of the character keys 2 when the shift keys 11 or 12 are actuated. After the key 11 has been actuated and is positioned in its locked position, the contacts Bu being closed again, the normal operation of the above described arrangement may be carried out so as to transmit code element combinations via the code element output means in the above described manner.

30

If it is desired, after characters have been typed and transmitted in the manner above while the self-locking key 11 has been in its depressed, locked position, to switch to the typing and transmitting of figures and symbols, then the shift key 12 is actuated whereby the lever 95 is sufficiently depressed to cause disengagement of the hook 102 from the holding member 103 so that after release of the shift key 12 also the key 11 returns to its normal position together with key 12. However, the actuation of key 12 and consequent depression of lever 95 has also caused, by the member 150 abutting against lever 95, the latter to be slightly depressed so that its extension 106 has again separated the contact members Bu whereby again an announcement signal, this time announcing the intended transmission of figures and symbols, is issued. At the same time a conventional blocking means is simultaneously operated so as to block all the character keys 2. The announcement signal in the international codes for announcing the transmission of figures differs from the coded signal announcing the transmission of letters. Therefore, either before the opening of the contact Bu or at least simultaneously therewith, the contact members of the contact Z₁ (FIGS. 3 and 5) arranged within the output line 52, are separated

in the following manner. An extension of the stem 104 of the key 12 carries a pin 107 movable in longitudinal direction and guided by the bracket 109 while being resiliently supported by the spring 105, and the pin 107 terminates in a blade 108 preferably of insulating material, which, as can be seen from FIG. 5, will wedge itself, upon depression of key 12, between the contact members of the contact Z_i and thereby interrupt the output line 52. Consequently the opening of the contact B_u will result in a signal composed of code elements transmitted only through the lines 50, 51, 53 and 54 to the code output elements 55, 56, 58 and 59, respectively, which is in accordance with the international code.

In those cases where the coding arrangement according to the invention is used for operating a perforator device for tape, as described and illustrated, and if it is desired that as a further step punched cards are punched or perforated in accordance with the perforation of the tape in the perforator HP, then it is necessary that, together with each operation of the carriage return, four different code signals are automatically transmitted and converted into corresponding coded perforations of the tape. For this purpose the automatic control arrangement illustrated in FIG. 2 is provided. The operation of this automatic control arrangement is started whenever by actuation of one of the carriage return keys 9 (FIG. 1) simultaneously the switch A (FIG. 2) is moved from its normal position shown in FIG. 2 to its second position. When this is done the capacitor C_I is able to discharge across the relay coil R_I . Consequently the corresponding relay contact r_1R_I is moved by the energization of the coil R_I to its second position whereby the capacitor C_A is placed between lines 19 and 20 and is correspondingly charged. However, in the meantime the capacitor C_I has discharged so that the contact r_1R_I returns again to its normal position as shown in FIG. 2. Hereby the now charged capacitor C_A is connected in circuit with the relay coil R_A so that the latter is energized by the discharge of capacitor C_A and moves the corresponding contact r_1R_A to its second position whereby, in a manner similar to that described above now the capacitor C_{II} is charged. In the meantime the capacitor C_A has discharged across the coil R_A so that the contact r_1R_A returns to its normal position whereby the relay coil R_{II} is energized by the discharge of the charged capacitor C_{II} . The same procedure repeats and continues in an analogous manner until also the relay coils R_3 and finally R_4 have been energized and again deenergized, while the corresponding contacts have been operated.

It will be understood that the automatic control according to FIG. 2 comprises two groups of relays, namely a group comprising the coils R_A to R_C and the other group comprising the coils R_I to R_{IV} . The second group is the actual control relay group and has therefore, in addition to the already mentioned contacts r_1R_I , r_1R_{II} and r_1R_{III} additional contacts as follows: The coil R_I operates also the normally closed contacts r_2R_I in line 24 and r_3R_I in line 30 (FIG. 3) which two contacts when opened would normally produce a signal indicating according to the international code the letter "S" but indicates also according to the code the signal "Bell"; the coil R_{II} also operates the normally closed contact r_2R_{II} which furnishes, when opened, a signal CR indicating "carriage return"; the coils R_{III} operates also a normally closed contact r_2R_{III} which furnishes, when open, a signal indicating according to the international code "LF" meaning "line shift"; finally the coil R_{IV} also operates two contacts, namely the normally closed contact r_2R_{IV} in line 22 and the normally closed contact r_3R_{IV} in line 31, the simultaneous opening of these last mentioned two contacts resulting in a coded signal indicating that "figures" are going to be transmitted in accordance with the depression of the key 12 as described above. It will now be understood that the consecutive operations

of the just mentioned control relays comprising the coils R_I to R_{IV} are timed and controlled by the operation of the first group of relays comprising the relays R_A to R_C so that predetermined time intervals are provided between the consecutive automatic operation of the control relays.

It will be understood that each of the elements described above, or two or more together, may also find a useful application in other types of a coding arrangement, particularly suitable for being incorporated in a business machine differing from the types described above.

While the invention has been illustrated and described as embodied in a business machine adapted to be used for printing different items of information such as characters, figures and symbols and comprising a coding arrangement, it is not intended to be limited to the details shown, since various modifications and structural changes may be made without departing in any way from the spirit of the present invention.

Without further analysis, the foregoing will so fully reveal the gist of the present invention that others can by applying current knowledge, readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In an information handling machine, particularly in a business machine adapted for printing different items of information such as characters including letters, figures and symbols, a coding arrangement, comprising, in combination, a plurality of information input means including each a type printing member movable between an idle position and a printing position, each of said information input means being respectively associated with a different item of information and each including at least one and a maximum of two normally closed circuit interrupting means, but at least one of said information input means including two of said circuit interrupting means, the circuit interrupting means of each particular information input means being associated with, and movable to open position by, a different one of said type printing members, a plurality of groups of said circuit interrupting means being formed each by series-connection of a different selection of said circuit interrupting means forming part of said plurality of information input means, each of said groups constituting a control circuit portion; a plurality of code element output means each individually changeable between an inoperative and an operative condition, selected combinations of at a given moment operative ones and inoperative ones of said code element output means, respectively, representing different code combinations respectively associated with different ones of said items of information; a source of energy; and circuit means operatively interconnecting said source of energy, said control circuit portions formed by said groups of circuit interrupting means and said code element output means for changing selected combinations thereof between inoperative and operative condition so as to represent thereby a selected code combination corresponding to a selected item of information whenever a type printing member associated with that particular selected item of information is moved to printing position, the respectively associated circuit interrupting means being thereby moved to open position, the movement of at least one and a maximum of two predetermined selected circuit interrupting means causing said change of the corresponding code element output means from inoperative to operative condition.
2. A coding arrangement as claimed in claim 1, said circuit means further including selector means responding to actuation of any one of said information input means and to the resulting actuation of the respective

75

circuit interrupting means irrespective of the duration of the resulting circuit interruption, and for rendering, upon actuation of a particular one of said information input means, at least one selected one of said code element output means ready for being changed from inoperative to operative condition so as to predetermine thereby a particular combination of operative and inoperative code element output means which represents the same item of information as said particular actuated information input means, and control means actuatable by any one of said information input means for connecting, upon actuation of said particular information input means, said source of energy with those selected code element output means which are rendered ready for being changed from inoperative to operative condition within said particular combination thereof, and for thereby effecting the change of said selected code element output means from inoperative to operative condition, whereby a code signal is delivered by said selected code element output means which represents the same item of information as the particular information input means that is being actuated for printing such item.

3. A coding arrangement as claimed in claim 2, wherein in said selector means comprise a plurality of relay means, each of said relay means having a normally energized coil connected with said source of energy in series with a predetermined number of said circuit interrupting means, and a plurality of switch means held in a first position as long as the respective coil is energized and moving to a second position when the respective coil is deenergized, at least one of said switch means of each of said relay means being connected between said information output means and at least one of said code element output means, respectively, for closing a circuit portion between said information input means and the respective code element output means when the respective switch means is in its second position.

4. A coding arrangement as claimed in claim 3, wherein in said circuit means include automatic control means comprising a plurality of second relay means in cascade arrangement, each of said second relay means being connected to be energized by said source of energy and each comprising a coil, a capacitor and a first switch movable between one position disconnecting the respective coil and connecting the respective capacitor with said source of energy for charging the same, and another position disconnecting the respective capacitor from said source and connecting the same in series with the respective coil so as to cause energization thereof by discharge of the respective capacitor, each of said first switches of said second relay means, with the exception of one thereof, being movable from said other position to said one position by energization of the coil of a different one of said coils of said second relay means while returning automatically to said other position upon deenergization of the respective coil, said first switch of said one excepted relay means being normally in said one position and being movable manually into said other position, a selected group of said second relay means, including said excepted one, having at least one second normally closed switch movable to open position upon energization of the respective coil and connected in series with said series of circuit interrupting means connected with the normally energized coils, respectively, of selected ones of said relay means of said selector means.

5. A business machine as claimed in claim 4, wherein in said information input means further comprise a shift key means, and a self-locking shift key means operable independently of said shift key means, and a control member operable by either one of said shift key means and self-locking shift key means, and wherein said circuit means comprise a normally closed switch device connected in the circuit between said source of energy and said selector means and operatively arranged relative to said control member so as to be moved to open position

when said control member is actuated by operation of either one of said shift key means and self-locking shift key means, whereby a plurality of said code element output means are changed to operative condition simultaneously; wherein said self-locking shift key means are so constructed that said switch device is moved to open position by said control member only temporarily during the operation of said self-locking key means shortly before the latter reaches its locked position; wherein said self-locking shift key means comprises means for preventing the operation of those of said key members which are associated with items of information comprising figures and symbols; wherein said shift key means comprises means for preventing the operation of those of said key members which are associated with items of information comprising characters; and wherein said shift key means comprises an actuating member, and a normally closed switching device operable by said actuating member so as to open the respective circuit when said shift key means is operated, said switching device being connected in circuit with one selected one of said code element output means, whereby upon operation of said shift key means alone all of said code element output means except said selected one are changed from inoperative to operative condition; said business machine further comprising a main switch for rendering said source of energy operative with respect to said circuit means, and a control member operatively connected with said main switch for actuating the latter and arranged in the area of said keyboard, and including blocking means operatively connected with said control member for being actuated together with said main switch, said blocking means serving to prevent operation of those of said key members which are associated with items of information which are not to be converted into code element combinations.

6. A coding arrangement as claimed in claim 3, wherein for each of said code element output means a different one of said relay means is provided and respectively associated therewith, said one switch means of each of said relay means being connected between said information input means and the respectively associated code element output means, and wherein additional ones of said relay means are provided and associated respectively with a plurality of said code element output means, said additional relay means including a plurality of switch means connected between said information input means and a predetermined plurality of said code element output means for closing a circuit portion between said information input means and a plurality of said code element output means when the respective plurality of switch means is in their second position.

7. A coding arrangement as claimed in claim 2, wherein in said selector means comprise a plurality of relay means, each of said relay means having a normally energized coil connected with said source of energy in series with a predetermined number of said circuit interrupting means, and a plurality of switch means held in a first position as long as the respective coil is energized and moving to a second position when the respective coil is deenergized, at least one of said switch means of each of said relay means being connected between said control means and at least one of said code element output means, respectively, for closing a circuit portion between said information input means and the respective code element output means when the respective switch means is in its second position.

8. A coding arrangement as claimed in claim 1, wherein in said normally energized relay means are constructed to operate with extremely rapid cut-off when deenergized, and with slow return when energized thereafter.

9. A coding arrangement as claimed in claim 3, wherein in said information input means comprise a control relay having a coil and at least one switch contact means movable from a circuit-opening position to a circuit-closing position when said coil of said control relay is energized,

said switch contact means being connected between said source of energy and said circuit portion so as to close a circuit between said source and at least said one of said switch means of any one of said relay means which is in said second position, said information input means further comprising an impulse source and an auxiliary-circuit means connected with said coil of said control relay and including a plurality of series-connected switch means, each of said series-connected switch means being held in a first position by a different one of said normally energized coils, respectively, of said relay means so as to prevent energization of said coil of said control relay, and being moved, upon deenergization of the respective one of said relay means, to a second position in which said auxiliary circuit is closed between said coil and said impulse source so as to energize said control relay.

10. A coding arrangement as claimed in claim 9, wherein said information input means comprise a control relay having a coil and at least one switch contact means movable from a circuit-opening position to a circuit-closing position when said coil of said control relay is energized, said switch contact means being connected between said source of energy and said circuit portion so as to close a circuit between said source and at least said one of said switch means of any one of said relay means which is in said second position, said information input means further comprising an impulse source and an auxiliary-circuit means connected with said coil of said control relay and including a plurality of series-connected switch means, each of said series-connected switch means being held in a first position by a different one of said normally energized coils, respectively, of said relay means so as to prevent energization of said coil of said control relay, and being moved, upon deenergization of the respective one of said relay means, to a second position in which said auxiliary circuit is closed between said coil and said impulse source so as to energize said control relay.

11. A business machine as claimed in claim 10, wherein a tape feeding device is provided for moving a tape past said electromagnetic hole puncher devices, said tape feeding device comprising a drive motor and electromagnetic one-turn clutch means for controlling the driving action of said motor, and wherein said control relay has a second switch contact means movable from a circuit-opening position to a circuit-closing position when said coil of said control relay is energized, said second switch contact means being connected between said source of energy and said electro-magnetic clutch means for energizing the latter when said control relay is energized.

12. A coding arrangement as claimed in claim 11, wherein a switch is connected in parallel with said second switch contact means, for arbitrarily energizing said clutch means for an indefinite period independently of said control means.

13. A coding arrangement as claimed in claim 2, comprising a keyboard including a plurality of key members respectively associated and operatively connected with said type printing members for actuating the latter.

14. A coding arrangement as claimed in claim 13, comprising a main switch for rendering said source of energy operative with respect to said circuit means, and a control member operatively connected with said main switch for actuating the latter and arranged in the area of said keyboard.

15. A business machine as claimed in claim 14, including blocking means operatively connected with said control member for being actuated together with said main switch, said blocking means serving to prevent operation of those of said key members which are associated with items of information which are not to be converted into code element combinations.

16. A coding arrangement as claimed in claim 13 wherein said information input means further comprise a shift key means, and a self-locking shift key means operable independently of said shift key means, and a

control member operable by either one of said shift key means and self-locking shift key means, and wherein said circuit means comprise a normally closed switch device connected in the circuit between said source of energy and said selector means and operatively arranged relative to said control member so as to be moved to open position when said control member is actuated by operation of either one of said shift key means and self-locking shift key means, whereby a plurality of said code element output means are changed to operative condition simultaneously, said self-locking shift key means comprising means for preventing the operation of those of said key members which are associated with items of information comprising figures and symbols.

15. A business machine as claimed in claim 16, wherein said self-locking shift key means are so constructed that said switch device is moved to open position by said control member only temporarily during the operation of said self-locking key means shortly before the latter reaches its locked position.

18. A coding arrangement as claimed in claim 13, wherein said information input means further comprise a shift key means, and a self-locking shift key means operable independently of said shift key means, and a control member operable by either one of said shift key means and self-locking shift key means, and wherein said circuit means comprise a normally closed switch device connected in the circuit between said source of energy and said selector means and operatively arranged relative to said control member so as to be moved to open position when said control member is actuated by operation of either one of said shift key means and self-locking shift key means, whereby a plurality of said code element output means are changed to operative condition simultaneously, said self-locking shift key means comprising means for preventing the operation of those of said key members which are associated with items of information comprising characters.

19. A business machine as claimed in claim 16, wherein said shift key means comprises an actuating member, and a normally closed switching device operable by said actuating member so as to open the respective circuit when said shift key means is operated, said switching device being connected in circuit with one selected one of said code element output means, whereby upon operation of said shift key means alone all of said code element output means except said selected one are changed from inoperative to operative condition.

20. In an information handling machine, especially in a business machine adapted to be used for printing different items of information such as letters in lower and upper case, figures and symbols, and to issue corresponding output signals respectively representing such items of information, a control arrangement, comprising, in combination, keyboard means including a plurality of key members respectively associated with said different items of information for selectively causing printing of the respective items of information and for causing the release of corresponding output signals; a first shift key means for causing when actuated said key members to print upper case letters and symbols, respectively, instead of lower case letters and figures, respectively; and a self-locking second shift key means for causing when actuated said key members to print upper case letters and symbols,

60 for causing when actuated said key members to print upper case letters and symbols, respectively, instead of lower case letters and figures, respectively; and a self-locking second shift key means for causing when actuated said key members to print upper case letters and symbols, respectively, instead of lower case letters and figures, respectively, and being adapted to lock itself in actuated position until released, said self-locking second shift key means being actuatable independently of said first shift key means, and said first shift key means cooperating with said second shift key means in such a manner that when said first shift key means is actuated while said second shift key means is locked in said actuated position said second shift key means is released to its normal position, said self-locking second shift key means including

70 control contact means actuatable by the movement of

said second shift key means from its normal position toward said actuated position and adapted to cause issue of an advance output signal representing an advance announcement of transmission of output signals representing letters.

21. A control arrangement as claimed in claim 20, wherein said first shift key means includes actuating means cooperating with said second shift key means for causing when said first shift key means is actuated said second shift key means to actuate said control contact means.

22. A control arrangement as claimed in claim 21, wherein said actuating means are so adjusted that by actuation of said first shift key means said second shift key means when locked in actuated position is released to its normal position.

23. An arrangement as claimed in claim 22, wherein said first shift key means includes second control contact means actuatable by the movement of said first shift key means to its position in which said first mentioned control contact means is actuated, said second control contact means being adapted to change when actuated said advance output signal to a second advance output signal representing an advance announcement of transmission of output signals representing figures.

24. An arrangement as claimed in claim 23, wherein said control contact means are normally closed and said self-locking second shift key means includes an actuating member arranged for moving said control contact means to open position only at the end of the movement of said second shift key means before the latter assumes locked position and to permit return of said control contact means to closed position when said second shift key means assumes said locked position, and wherein said first shift key means includes a second actuating member arranged for moving said second control contact means to open position during actuation of said first shift key means at the latest simultaneously with the moving of said first mentioned control contact means to open position when this is effected by actuation of said first shift key means, said second actuating member being resiliently supported in said first shift key means so as to permit actuation of said second control contact means before actuation of said first mentioned control contact means.
